UNITED STATES PATENT OFFICE.

JOHN A. WELCH, OF AUSTIN, MISSOURI.

GATE.

SPECIFICATION forming part of Letters Patent No. 636,092, dated October 31, 1899.

Application filed July 21, 1899. Serial No. 724,627. (No model.)

To all whom it may concern:

Be it known that I, JOHN A. WELCH, a citizen of the United States, residing at Austin, in the county of Cass and State of Missouri, 5 have invented new and useful Improvements in Gates, of which the following is a specification.

This invention relates to certain new and useful improvements in gates; and it consists 10 in the construction and combination of the parts, as will be hereinafter set forth, and specifically pointed out in the claims.

In the accompanying drawings, which illustrate my invention, Figure 1 is a perspective 15 view of a gate embodying my improvements. Fig. 2 is a vertical sectional-view of a part of the gate-operating mechanism. Fig. 3 is a plan view of a plate carried by one of the gate-posts. Fig. 4 is a detail view showing 20 the form of catch with which the gate-latch engages, and Fig. 5 is a detail perspective view of the housing or cover for a part of the gate-operating mechanism.

A refers to one of the gate-posts, which is 25 provided with a recess *a*, having therein a depression *a'* and inclined portions *a''*, upon which the gate-latch will ride before entering the recess or depression *a'*. The upper portion of the recess *a* is constructed to present a 30 central depending portion immediately above the depression *a'* and inclinations which spring downwardly therefrom, as will more fully appear by reference to Fig. 4 of the drawings.

The latch-post A has near its base a cross-piece A', the ends of which are inclined downward, and upon said cross-piece and the catch 35 the gate is adapted to rest when closed.

To the gate-post B, located on the opposite 40 side of the gateway from the latch-post A, is rigidly secured a plate B', said plate having near its central portion a rectangular opening, through which the upper end of the post passes. The plate is provided with a slot B'', 45 the sides of which converge and join at the front portion of the plate, and said plate is also provided with a recess *b'*, which is adapted to receive the end of a bolt. The forward portion of the plate B' is angular and its rear 50 portion is semicircular, as shown in Fig. 3, which construction provides at the junction of the circular part with the angular sides

laterally-projecting portions, against which a lever or bar D will abut to limit the swinging movement of the gate and lever.

The gate C is preferably made of gas-pipe or other tubular material, and the end bar *c* of the frame thereof inclines, as shown, and projects above and below the horizontal bars of the gate. The lower end of the bar *c* passes 60 through an eyebolt near the base of the post B, and the upper end passes through the slot B'' and projects slightly above the plate B', so as to engage with a lever pivoted on a line with the post B. To the front end of the gate 65 is pivoted a suitably-constructed latch.

Above the rectangular portion of the post B, whereon is secured the plate B', said post is reduced to provide a pivot-pin *d*, and upon said pivot-pin is fulcrumed a bar or lever D, 70 having through one end an elongated slot *d'*, through which the upper end of the end bar of the gate passes. The rear portion of the bar D is cut away beyond the plate, so as to receive in said cut-away or recessed portion 75 a bolt D', said bolt being supported in suitable bearings and having thereon a spring, the tendency of which is to shoot the bolt toward the gate, so that its end may enter the recess *b'* in the plate. The rear end of the 80 bolt is bent so as to extend upward, passes through an opening *d''* in the bar D, and has attached thereto strings or cords for retracting the bolt. Immediately above the bar D is a washer *e*, and above said washer on the 85 pin *d* is a bar E, which has therethrough a slot *e'*, and an opening through which passes a bolt F, said bolt having a rectangular head, and an opening *f*, through which are guided the cords attached to its upwardly-projecting 90 end. The bolt F has offsets *f'* and below said offsets a stem with a threaded end for the reception of a nut.

Upon the bolt F, above the reduced end of the bar D, are the inner ends of rods G G, 95 said rods being held in pivotal engagement with the bar D. These rods pass through openings in posts H H, located adjacent to the gateway, and the flexible connections or cords, which extend from the bolt D' through the 100 head of the bolt F, are guided through suitable staples or eyes carried by the rods G and depend through the looped ends thereof. When the latch is drawn out of the recess

b', the lever or bar D may be swung upon its pivot, and its swinging movement is limited by the depending portion thereof engaging one of the projecting portions of the plate, 5 thereby preventing the lever from assuming a position or angle which would render it difficult to operate the same by the rod.

To the bar D may be attached a suitable housing comprising a pair of inclined boards, 10 which are attached to strap-iron supports, the horizontal portions thereof being attached to the sides or upper portion of the bar D, so that said housing will move in unison with the bar and cover the parts carried thereby, 15 so as to protect them from the weather.

In operation, supposing the gate to be closed, a person in a vehicle or on horseback approaching the gate draws upon the flexible connection which depends from the rod G, 20 which draws the bolt out of the recess *b'* in the plate B'. Then by drawing upon the flexible connection or rod G the end of the bar D to which the rod G is connected is moved toward the operator and the other end carries 25 the end bar of the gate into one of the inclined portions of the slot, so that the forward end of the gate will be raised, which frees the latch from its catch and changes the center of gravity of the gate, so that it will 30 swing open. When it is desired to close the gate, the opposite rod is drawn upon, which will cause the gate to swing on a line with the posts, the bolt automatically engaging its recess to hold the bar D on a line with the gate. 35 A person on foot can open the gate by simply raising the latch and pressing upon the gate, and after said person has passed through the gateway the gate will automatically close. By having the end bar of the gate inclined 40 from its base outward there is no necessity of providing latches on the posts H, as the center of gravity is changed, so that the gate will remain open until the rods G are moved to bring the lever or bar D on a line with the 45 fence.

Having thus described my invention, what I claim as new, and desire to secure by Letters Patent, is—

1. The combination with a gate having an 50 end post which inclines away from the post to which it is attached, a plate carried by the gate-post and provided with an angular slot on one side of its center and on its opposite side a bolt-recess, a bar pivoted to the gate- 55 post above the plate, said bar having at one end an elongated slot and at the other end operating-rods which are pivoted thereto, a spring-actuated bolt carried by said pivoted bar, a brace-bar pivoted at one end to the

gate-post and secured at the other end to the 60 bolt on which the operating-rods are pivoted, said bolt having an aperture therethrough, flexible connections attached to the spring-actuated bolt and to the gate-operating rods which extend from the pivoted bar on each 65 side of the gate, the parts being organized substantially as shown and for the purpose set forth.

2. The combination with a swinging gate having an inclined end bar, of a plate attached to the upper end of a fence-post and provided with a slot the sides of which converge and join, and opposite the slot with a recess, a bar pivoted above the plate and provided at one end with a slot, the end bar of 70 the gate engaging the plate and bar by being passed through the slots therein, a bolt carried by the bar, a spring for moving the bolt toward the plate, rods attached to the bar and flexible connections secured to the bolt and 80 to the rods, substantially as shown and for the purpose set forth.

3. The combination with a gate, of a fence-post provided with a plate having an angular slot through which one of the end bars of the 85 gate passes, the plate having shoulders adjacent to the ends of the angular slot, and a semicircular portion between said shoulders, a lever pivoted to the fence-post above the plate, said lever having a depending portion which 90 overlies the semicircular portion of the plate so that the lever will abut against the shoulders before the end bar of the gate reaches the end of the slot.

4. In gate-operating mechanism, the combination with a swinging gate and its guide-plate, of a lever which engages the gate and swings horizontally over the guide-plate, a latch carried by the lever for engagement with a recess in the guide-plate, said latch 95 having a vertical end which passes through an opening in the lever, a bolt attached to the end of the lever said bolt having a guide-opening, rods connected to the lever by the bolt, flexible connections attached to the latch 100 guided by the opening in the bolt and connected to the rods, a bar mounted upon the same pivot and attached to the bolt, said bar having a slot through which passes the vertical end of the latch-bar, substantially as 105 shown.

In testimony whereof I have hereunto set my hand in presence of two subscribing witnesses.

JNO. A. WELCH.
